UNITED STATES PATENT OFFICE.

INEVA T. REILLY, OF INDIANAPOLIS, INDIANA.

NECKTIE HOLDER.

Application filed August 4, 1921. Serial No. 489,812.

To all whom it may concern:

Be it known that I, INEVA T. REILLY, citizen of the United States, residing at Indianapolis, in the county of Marion and 5 State of Indiana, have invented certain new and useful Improvements in Necktie Holders; and I do declare the following to be a full, clear, and exact description of the invention, such as will enable others skilled in 10 the art to which it appertains to make and use the same.

This invention relates to an improved necktie holder and one object of the invention is to provide a holder which is so constructed that the neckties may be placed flat upon the holder and folded over the upper end of the holder, clamps being provided upon the upper and lower faces of the holder board for engaging the end portions of the tie and not only serving to retain the neckties in engagement with the holder board but also serving to hold the neckties stretched so that creases will be removed from the neckties.

25 Another object of the invention is to provide a holder which can be stamped from sheet material and thus very cheaply produced.

Another object of the invention is to provide a necktie holder which will be simple in construction and very easy to operate and which will be light and durable.

This invention is illustrated in the accompanying drawing, wherein:

35 Figure 1 is a view showing the necktie holder looking at the outer face thereof.

Figure 2 is a view showing the necktie holder in side elevation.

Figure 3 is a view showing the necktie 40 holder in upper end elevation.

This improved necktie holder is provided with a body portion 1 in the form of a flat and relatively thin board which may be formed of any suitable material and may be 45 either wood, sheet metal, composition or any other material. Upon the upper face of the board or body 1, there has been provided a relatively large spring clamp 2 which extends transversely of the board as shown in 50 Fig. 1 and is curved longitudinally as shown in Figs. 2 and 3 so that a necktie may be easily passed between the board and clamp 2 and the neckties securely gripped by the clamp and held in engagement with the board. Upon the under face of the board

there has been provided a second clamp 3 which is a relatively small clamp and extends transversely of the board. This clamp 3 is curved longitudinally similar to the clamp 2 as shown in Fig. 3 and as shown in 60 Figs. 1 and 2 is located above the clamp 2. It should be further noted that this clamp 3 has its free end portion extending in an opposite direction to the free end portion of the clamp 2 thus permitting the necktie to 65 be easily put in place and gripped by the clamp 2 and then stretched upon the board and moved into engagement with the clamp 3. When this device is in use, a necktie of the four-in-hand type will be doubled with 70 one end terminating short of the second end. Of course, the tie may be doubled with the ends brought together if desired but in the preferred form, the tie will be doubled with one end terminating short of the second 75 end. After the tie has been doubled, it will be placed upon the outer face of the board and slipped beneath the clamp 2 so that the end portions of the tie will be firmly gripped by this large clamp. The doubled 80 portion of the tie will then be drawn tightly upon the board and carried over the upper end of the board and brought into contact with the underface of the board so that the doubled portion of the tie can be slipped 85 into the engagement with the smaller clamp 3. The tie will thus be firmly gripped and will be held tightly stretched upon the board so that all wrinkles will be removed 90 when the tie is taken off of the board. After one tie has been put in place, others can be folded and put in place. It will thus be seen that the board will serve to carry one tie or if desired more than one tie. The 95 clamps may be formed of any suitable resilient material and connected with the board in any desired manner.

I claim:

1. A necktie holder and stretcher comprising a flat board for having a necktie placed longitudinally thereon and doubled over one end, and separate tie-gripping means upon opposite faces of said board and in approximately the central portion thereof.

2. A necktie holder and stretcher comprising a flat board for having a necktie placed longitudinally thereon and doubled over one end, and tie gripping means upon opposite faces of said board, each of said

tie gripping means being in the form of a resilient tongue extending transversely of the board and curved longitudinally.

3. A necktie holder and stretcher comprising a flat board for having a necktie placed longitudinally thereon and doubled over one end, and tie gripping tongues upon the opposite faces of the board extending transversely thereof and curved longitudinally,

the tongue upon one face of the board being of a different length than the tongue upon the second face of the board and having its free end portion extending in an opposite direction to the free end portion of the last mentioned tongue.

In testimony whereof I have hereunto set my hand.

INEVA T. REILLY.
